MATERIAL BREAKING CARTRIDGE

James C. Hesson, Riverdale, and John L. Smith, Chicago, Ill., assignors to Cardox Corporation, Chicago, Ill., a corporation of Illinois

Application August 20, 1951, Serial No. 242,724

34 Claims. (Cl. 102—25)

This invention relates to new and useful improvements in material breaking cartridges of the type employing a high pressure gas as the work performing medium.

The use of cartridges employing a highly compressed charge of air or other gases for breaking down materials, such as coal in mines, is well-known and has been widely practised in recent years. The gaseous charge for such cartridges may be introduced after the cartridge is positioned for operation or may be produced within the cartridge at the time of operation by expansion of a previously introduced liquefied gas or by burning or heating a previously introduced solid of a type which will thereupon produce a large volume of gas. In any event, the efficiency of this type of operation is dependent to a considerable degree upon the speed and extent of opening of the valve employed for effecting the release of the charge of compressed gas and upon the ease with which the cartridge can be reconditioned for subsequent use.

The primary object of the invention is to provide a compressed gas material breaking cartridge from which the material breaking charge can be quickly and completely released and which can be reconditioned for subsequent and repeated use with a minimum of time and effort.

A further important object of the invention is to provide a compressed gas material breaking cartridge having a release valve mechanism, located entirely in the discharge end of the cartridge, which will operate automatically at the desired work performing pressure and which may be quickly reconditioned for subsequent use.

Another important object of the invention is the provision of a material breaking cartridge that may be charged with gas at a continually increasing pressure, and is provided with a valve mechanism which will operate automatically to quickly effect release of the complete material breaking charge when the pressure of the gas reaches a predetermined value and which may be quickly reconditioned for use to effect release of a subsequent charge at the same predetermined pressure.

Another important object of the invention is to provide a compressed gas material breaking cartridge, the discharge from which is controlled by a rupturable member which will operate automatically to effect discharge only at the desired work performing pressure, the rupturable member being readily movable into a number of different positions for repeated use to recondition the cartridge for subsequent operations and being readily replaceable by a like member which in turn may be repeatedly used for a plurality of operations.

A still further object of the invention is to provide a material breaking compressed gas cartridge having a charge releasing valve mechanism which will operate automatically to effect discharge of the gas when the pressure of the charge exceeds the rupture strength of an element of the valve mechanism, the rupturable element being both movable and replaceable to quickly recondition the valve mechanism for a multiplicity of subsequent charge releasing operations.

2

Other objects and advantages of the invention will be apparent during the course of the following description.

In the accompanying drawings forming a part of this specification and in which like reference characters are employed to designate like parts throughout the same,

Figure 1 is a perspective view of one form of material breaking cartridge embodying the invention,

Figure 2 is a longitudinal sectional view of the cartridge illustrated in Fig. 1,

Figure 3 is a transverse sectional view taken on line 3—3 of Fig. 2,

Figure 4 is a longitudinal sectional view of the discharge end portion of a modified form of material breaking cartridge,

Figure 5 is an end elevational view of the cartridge illustrated in Fig. 4,

Figure 6 is a transverse sectional view taken on line 6—6 of Fig. 4,

Figure 7 is a longitudinal sectional view of the discharge end portion of a further modified form of material breaking cartridge,

Figure 8 is a transverse sectional view taken on line 8—8 of Fig. 7,

Figure 9 is a longitudinal sectional view of the discharge end portion of a still further modified form of material breaking cartridge,

Figure 10 is an enlarged sectional view taken on line 10—10 of Fig. 9, and

Figure 11 is a transverse sectional view taken on line 11—11 of Fig. 10.

In the drawings, wherein for the purpose of illustration are shown the preferred embodiments of the invention, and first particularly referring to Figs. 1 to 3, inclusive, the reference character 12 designates a cartridge body member having a chamber 13 therein from which the compressed gas charge is to be released. One end of the body member 12 is closed by a charging cap 14 which is threadedly connected to the body member. The charging cap 14 has an inlet opening 15 formed in its end wall and a conical seating surface 16 surrounding the outer end of the opening. An internally and externally threaded annular projection 17 extends axially outwardly from the end of the charging cap 14 in concentric relationship with the conical seating surface 16.

45 A guard ring 18 and a coupling nut 19 are slipped successively over the end of a compressed gas feed line 21 through which gas is to be fed into the chamber 13. The nut 19 is provided with an axially located bore 22 which is fitted onto the outer surface of the feed line 21 and the inner end portion of the bore 22 is flared outwardly to form a conical surface 23 opposite the conical seating surface 16. When the coupling nut 19 is threaded into the annular projection 17 the end of the feed line 21 is flared outwardly and gripped between the conical surfaces 16 and 23. The guard ring 18 is then threaded onto the projection 17 to form a protecting wall around the coupling members.

55 The illustrated charging cap 14 and its associated coupling elements comprise only one of several well-known methods of providing a charge of compressed gas in the chamber 13 and it is to be understood that applicants' invention is not to be limited to the particular means disclosed. It is contemplated that the invention, also, may be used with equal efficiency in those circumstances where the charge of compressed gas is introduced to the chamber 13 in the form of a liquefied gas or a solid which will form a large volume of gas when burned or heated.

60 The end portion of the body member 12 opposite the charging cap 14 is internally shouldered at 24 and is provided with threads 25 between the shoulder 24 and the adjacent end of the cartridge body. An adaptor member 26 is threaded into the end of the body member 12 into

sealing engagement with the gasket 27 positioned on the shoulder 24. The outer end portion of the adaptor member 26 is externally threaded at 28 and the end edge forms an annular valve seat 29.

A discharge section 31, formed with an internally threaded inner end portion 32, is threaded onto the end of the adapter and is provided with a circumferentially aligned row of discharge or release ports 33 which are closely adjacent to the valve seat 29 and are of sufficient number and total cross-sectional area to effect rapid release of the gas from the cartridge chamber 13. The discharge section 31 is of tubular construction and has an inner diameter slightly greater than that of the annular valve seat 29.

A piston type main valve 34 is positioned in the discharge section 31 for longitudinal movement relative thereto between its seated and fully opened positions. The valve 34 is of hollow cylindrical construction to reduce its weight to a minimum and has an open inner end and a closed outer end. The open inner end of the valve is beveled at its periphery to provide a seating surface 35 for engagement with the valve seat 29. The closed outer end portion of the valve has a packing ring 36 positioned in the circumferential groove 37 to provide sealing engagement between the valve and the inner surface of the discharge section 31 at all times. The valve 34, therefore, provides a seal between the discharge ports 33 and the interior of the discharge section and, when in its closed position, between the discharge ports and the charge release chamber 13.

A plunger 38 is positioned in the opposite end of the discharge section 31 from the main valve 34 for longitudinal movement relative to the section. The plunger 38 is formed with a circumferential groove 39 for receiving a packing ring 41 to provide sealing engagement between the plunger and the inner surface of the discharge section 31. Positioned between the main valve 34 and plunger 38 is a spring 42 which reacts to urge the valve and plunger toward opposite ends of the discharge section 31.

Threadedly connected to the outer end of the discharge section 31 is a double-ended venting cap 43 having an intermediate wall 43a for retaining the plunger 38 within the discharge section. The wall 43a is provided with an axially located aperture 44 for receiving an axial projection 45 on the outer end of the plunger 38. The projection 45 is movable in the aperture 44 to a position at which its outer end extends slightly beyond the outer face of the venting cap wall 43a.

Formed within the discharge section 31 and between the movable main valve 34 and plunger 38 is a control chamber 46 which is in communication with the charge release chamber 13 through an aperture 47 in the closed outer end of the main valve 34. A passageway 48 extends axially through the body portion of the plunger 38 and its projection 45. The diameter of the aperture 47 in the valve 34 is less than that of the passageway 48 in the plunger 38 for reasons that later will be described. Ratios of the aperture diameter to the passageway diameter ranging from one-half to one-third have been found to be satisfactory.

The outer end portion 49 of the venting cap 43 is internally threaded and is provided with diametrically positioned rectangular slots 51 which are located adjacent the wall 43a and have their major dimension parallel to said wall. A shear strip 52 of any suitable rupturable material, such as brass, steel, fiber, or the like, is inserted through the slots 51 across the end of the passageway 48 in the plunger 38. The strip 52 bears against the outer end of the projection 45 on the plunger 38 and is loosely clamped in this position by a plug 53 which is threaded into the end portion 49. The plug 53 is threaded into the cap portion 49 until it bears against the strip 52 and moves the strip and the plunger 38 a slight distance against the pressure of the spring 42.

The plug 53 is formed with an axially located passageway 54 of equal size and in alignment with the passageway 48 in the plunger 38 on the opposite side of the strip 52. The outer end of the passageway 54 intersects a transverse passageway 55 through the outer end of the plug 53. Radial ports 56 extend from the passageway 54 to the threaded periphery of the plug 53 to blow dust out of the threads and similar ports 57 extend from the passageway 54 into the space between the inner end of plug 53 and the venting cap wall 43a to blow dust out of the space.

The operation of the cartridge illustrated in Figs. 1 to 3, inclusive, when compressed air, or other gas, is employed, will be described as follows:

15 The cartridge, in an uncharged condition but connected to a suitable source of supply of compressed air, or other gas, by the feed line 21, is placed in the previously prepared drill hole formed in the working face of the material to be broken down, such as coal in a mine. At 20 this time, the charge release chamber 13 of the cartridge body 12 is sealed from the discharge ports 33 by the engagement of the main valve 34 with its seat 29 and by the packing ring 36. The charge release chamber 13, however, is in communication with the control chamber 25 46 through the aperture 47 in the valve.

The compressed air delivered to the charge release chamber 13 will rapidly build up the pressure therein to the desired work performing pressure. During this charging of the chamber 13, compressed air is permitted to 30 flow into the control chamber 46 through the aperture 47 in the valve 34. The pressures in the charge release chamber 13 and the control chamber 46, therefore, will be substantially equal during charging. At this time, the main valve 34 will be maintained in its seated or closed 35 position by the force of the spring 42 and the differential force acting upon the opposite ends of the valve. In other words, the effective surface area of the valve 34 exposed to the pressure in the control chamber 46 is greater than the effective surface area of the valve exposed to the pressure in the charge release chamber 13 40 to that the forces acting upon the valve 34 are unbalanced in a direction to maintain the valve in its closed position. These effective surface areas on opposite ends of the valve 34 may be considered as being equal to the cross-sectional area of the control chamber 46 and the cross-sectional area of the valve seat 29, respectively, 45 with each of the cross-sectional areas being reduced by the cross-sectional area of the aperture 47.

When the charge release and control chambers 13 and 50 46, respectively, have received a sufficient volume of gas to raise the pressures therein to the desired work performing value, the pressure of the gas in the control chamber will cause the exposed portion of the strip 52 to be sheared and blown through the passageways 54 and 55 to clear these passageways for the proper venting of the control chamber. It will be understood that the pressure at which shearing occurs will be controlled by the strength, character and thickness of the material from which the strip is made. Different types of strips 52 may, therefore, be employed to cause the cartridge to discharge 55 at any work performing pressure desired.

When the exposed portion of the strip 52 is sheared, the control chamber 46 is opened directly to the passageways 54 and 55 of the plug 53 so that the compressed gas will 60 flow through these passageways to quickly reduce the pressure in the control chamber. This reduction in the pressure in the control chamber 46 permits the pressure of the compressed gas in the charge release chamber 13 to unseat and completely open the valve 34 and release the 65 gas charge through the discharge ports 33. Upon discharge of the cartridge, the flow of gas through the feed line 21 will be cut off by an operator at a remote point 70 in the line.

The strip 52, which is initially clamped in position in 75 the slots 51 only by the pressure of the spring 42, is

clamped in position with a considerably greater force during charging of the cartridge by the pressure of the gas in the control chamber 46 acting on the plunger 38. When the cartridge is discharged, however, the pressure in the control chamber 46 is reduced to atmospheric pressure and the strip 52 is again clamped only by the pressure of the spring 42 on the plunger 38. The plug 53, therefore, may be loosened or moved outwardly by hand to permit the plunger 38 to move outwardly until it bears against the wall 43a so that further movement of the plug will release the strip 52 which then may be moved longitudinally in the slots 51 to position an unsheared portion across the aligned passageways 48 and 54. This repositioning of the strip 52 may be facilitated by marking or indexing the strip and the length of the strip may be such as to permit its use for any reasonable number of cartridge operations, such as from two to six. When the strip has been repositioned, the plug 53 is again tightened to move the strip 52 and plunger 38 a sufficient distance for the strip to be clamped by the action of the spring 42 on the plunger. At this time, the main valve 34 having been reseated by the spring 42, the cartridge is reconditioned for a subsequent operation.

As was previously pointed out, the passageway 48 is of larger cross-sectional area than the aperture 47 so that the venting of gas from the control chamber 46 will greatly exceed the rate of flow of gas through the aperture 47. To further increase the rapidity of the venting of the control chamber 46, the inlet end of the passageway 48 is rounded to provide a better discharge coefficient.

Referring now to Figs. 4 to 6, inclusive, for a detail description of this modification of the invention, the cartridge body member 12 and its attached adapter member 26 are substantially identical to those illustrated in Figs. 1 to 3, inclusive, and, for that reason, the same reference characters have been applied to the corresponding parts.

A discharge section 58, having its internally threaded inner end portion 59 connected to the adapter member 26 by the threads 28, is provided with two spaced circumferential rows of discharge or release ports 61. As illustrated in Fig. 6, there may be six uniformly spaced ports in each row with the ports of each row circumferentially displaced from, or out of alignment with respect to, the ports of the other row. It will be noted that the discharge section 58 is of greater length than the discharge section 31 of Fig. 2. The reason for this will appear as the description proceeds.

A piston type main valve 62, positioned in the discharge section 58 for longitudinal movement relative thereto, is of sufficient length to cover both of the rows of ports 61. Otherwise, it is constructed the same as the valve 34 of Fig. 2, and the same reference characters will be applied to the corresponding parts.

A plunger 66, positioned in the opposite end of the discharge section 58 from the main valve 62 for longitudinal movement relative to the section, is of the same general construction as the plunger 38 of Fig. 2, the only difference being that the main body portion is reduced in axial dimension. Therefore, the same reference characters will be applied. A spring 69, positioned between the main valve 62 and the plunger 66, reacts to urge the valve and plunger toward opposite ends of the discharge section 58.

Threadedly connected to the outer end of the discharge section 58 is a double-ended venting cap 71 which is of identical construction to the venting cap 49 of Fig. 2 and the same reference characters have been applied thereto.

Formed within the discharge section 58, between the movable main valve 62 and the plunger 66, is a control chamber 74 which is of sufficient length to accommodate the main valve 62 when the latter is in its fully opened position.

This cartridge, also, is provided with a shear strip 52 which functions in the same manner as the shear strip of the cartridge of Fig. 2. Cooperating with the shear strip 52

is a plug 81 which differs structurally from the plug 53 of Fig. 2 only by having a reduced cylindrical projection 82 which cooperates with the projection 45 of the plunger 66 for clamping the shear strip 52. Therefore, the same reference characters have been applied to the other corresponding parts.

The operation of the cartridge illustrated in Figs. 4 to 6, inclusive, is identical to that of the cartridge illustrated in Figs. 1 to 3, inclusive, and, for that reason, will not be described. It will be noted, however, that because the discharge section 58 is provided with a double row of discharge ports 61 it is necessary for the main valve 62 to move a greater distance into the control chamber 74 to completely open the discharge ports.

The modification of the invention illustrated in Figs. 7 and 8 employs a body member 12, adapter member 26, discharge section 31, venting cap 43, and shear strip 52, which are substantially identical to those illustrated in Figs. 1 to 3, inclusive, and the same reference characters have been applied to corresponding parts of each.

The main valve 85 is of the piston type and is positioned in the discharge section 31 for longitudinal movement relative thereto between its seated and fully opened positions. The valve 85 is of hollow cylindrical construction and has a closed inner end and an open outer end. The inner closed end of the valve 85 is beveled at its periphery to provide a seating surface 89 for engagement with the valve seat 29. The length of the valve 85 is such that its open outer end portion lies on the opposite side of the discharge ports 33 from the seating surface 89. The outer open end portion of the valve 85 is formed with a circumferential groove 91 for receiving a packing ring 92 to provide sealing engagement between the valve and the inner surface of the discharge section 31 at all times. The valve 85, therefore, provides a seal between the discharge ports 33 and the interior of the discharge section 31 and, when in its illustrated closed position, between the discharge ports and the chamber 13.

The plunger 87 is positioned in the opposite end of the discharge section 31 from the main valve 85 for longitudinal movement relative to the section. One portion of the plunger 87 forms a piston 93 having a circumferential groove 94 for receiving a packing ring 95 to provide sealing engagement between the plunger and the inner surface of the discharge section 31. The body portion of the plunger 87 extends inwardly from the piston 93 into the open end portion of the main valve 85. Positioned over the body portion of the plunger 87 and between the valve 85 and the plunger, is a spring 86 which reacts to urge the valve and plunger toward opposite ends of the discharge section 31. A projection 96 extends outwardly from the piston portion 93 of the plunger 87 through the aperture 44 in the venting cap 43 and is adapted for movement to a point slightly beyond the end of the venting cap.

Formed within the discharge section 31 and between the movable main valve 85 and plunger 87 is a control chamber 97 which is in communication with the charge release chamber through the aperture 98 in the inner closed end portion of the main valve 85. The body portion of the plunger 87, its piston 93 and its outwardly extending projection 96 have an axial passageway 99 extending therethrough. The diameter of the aperture 98 in the valve 85 is smaller than that of the passageway 99. Ratios of aperture diameter to passageway diameter ranging from one-half to one-third have been found to be satisfactory. Radial ports 101 extend outwardly from the passageway 99 in the plunger 87 to that portion of the control chamber 97 which surrounds the body portion 70 of the plunger.

The plug 88 is threaded into the outer end portion 49 of the venting cap 43 to bear against the shear strip 52 and to move the strip and its engaging plunger projection 96 a slight distance against the pressure of the spring 86 and to clamp the strip in its proper position. The plug

88 is formed with an axially located passageway 102, the inner end portion of which is of equal size and in alignment with the plunger passageway 99 on the opposite side of the strip 52. The outer end portion of passageway 102 is enlarged and intersects a transverse passageway 103 through the outer end portion of the plug 88. Radial ports 104 extend from the passageway 102 to the engaging threaded surfaces of the plug 88 and the cap end portion 49 to blow dust out of the threads.

The operation of the cartridge illustrated in Figs. 7 and 8 is identical to that of the cartridge illustrated in Figs. 1 to 3, inclusive, and will not be described. It will be noted, however, that the radial ports 101 in the body portion of the plunger 87 facilitate the rapid venting of the air from the control chamber 97 which would otherwise be inhibited by the elongated body portion of the plunger 87.

Referring now to Figs. 9 to 11, inclusive, wherein is illustrated a further modification of the invention, it will be noted that the cartridge body member 12, adapter member 26, and discharge section 31 are substantially identical to those illustrated in Figs. 1 to 3, inclusive, and the same reference characters have been applied to the corresponding parts thereof.

A venting extension 105, having an internally threaded inner end portion 106 screwed onto the outer end portion of the discharge section 31, provides a circumferentially aligned row of venting ports 107 closely adjacent to the outer end of the discharge section 31. The venting extension 105 is of tubular construction and has an inner diameter slightly greater than that of the discharge section 31 so that the end of the discharge section is slightly offset inwardly from the inner surface of the venting extension to form a pilot valve seat 108.

A piston type main valve 109 is positioned in the discharge section 31 for longitudinal movement relative thereto between its seated and fully opened positions. The main valve 109 is of hollow cylindrical construction and has an open inner end and a closed outer end. The open inner end of the valve is beveled at its periphery to provide a seating surface 111 for engagement with the valve seat 29. The length of the valve 109 is such that its closed outer end portion lies on the opposite side of the discharge ports 33 from the valve seat 29. The closed outer end portion of the valve 109 is formed with a circumferential groove 112 for receiving a packing ring 113 to provide sealing engagement between the valve and the inner surface of the discharge section 31 at all times. The valve 109, therefore, provides a seal between the discharge ports 33 and the interior of the discharge section 31 and, when in its closed position, between the discharge ports and the chamber 13.

Positioned in the discharge section 31 in engagement with the outer end of the main valve 109 is a spring 114 which is retained in the discharge section by a piston type pilot valve 115. The spring 114 is compressed between and reacts in opposite directions against the main valve 109 and the pilot valve 115 to urge the main and pilot valves, respectively, toward and away from their valve seats 29 and 108.

The pilot valve 115 is positioned in the venting extension 105 for longitudinal movement relative thereto between its seated and full opened positions and is of hollow cylindrical construction similar to that of the main valve 109. The inner open end portion of the pilot valve 115 is beveled at its periphery to provide a seating surface 116 for engagement with the pilot valve seat 108. The outer closed end portion of the valve 115 is formed with a circumferential groove 117 for receiving a packing ring 118 to provide sealing engagement between the pilot valve and the inner surface of the venting section 105 at all times. The pilot valve 115, therefore, provides a seal between the venting ports 107 and the interior of venting section 105 and, when in its closed position, between the venting ports and the interior of the discharge section 31.

A spring 119 is positioned in the venting section 105 with one of its end portions engaging the outer end of the pilot valve 115 and a plunger 121 is positioned in the venting section for engagement with the opposite end of the spring. The spring 119 is, therefore, compressed between and reacts in opposite directions against the pilot valve 115 and the plunger 121 to urge the valve and plunger toward opposite ends of the venting section 105. The spring 119 is somewhat stronger than the spring 114 so that the unbalanced forces acting upon the pilot valve 115 will cause the valve to move into the position in which the seating surface 116 engages the valve seat 108.

The plunger 121 is adapted for longitudinal movement in the venting section 105 and is formed with a circumferential groove 122 for receiving a packing ring 123 to provide sealing engagement between the plunger and the inner surface of the venting section.

Threadedly connected to the outer end of the venting section 105 is a double-ended venting cap 124 which retains the plunger 121 within the venting section. The venting cap 124 is provided with an axially located, internally threaded pocket 125 extending through its outer end portion 124a. The inner reduced portion 125a of the pocket 125 is smooth and receives a projection 126 on the outer end of the plunger 121 which is movable to a position at which its outer end extends slightly into the threaded portion of the pocket.

Diametrically opposite, outwardly opening recesses 127 are formed in the sides of the cap end portion 124a and are connected with the threaded portion of the pocket 125 by the slots 128, as best illustrated in Fig. 10. On opposed sides of each recess 127, the cap 124 is cut away to provide the webs 129.

The recesses 127 are provided to removably house the supply and take-up reels 139 which are rotatably supported by the shafts 137 that are insertable in the aligned bearing openings 138 formed in the webs 129. The hubs of the reels 139 are provided with suitably attached keys 141. The shafts 137 are formed with keyways to receive the keys 141. It will be appreciated that the shafts 137 may be inserted through their bearing openings 138 and through the bores of the reel hubs to mount the reels 139 in the recesses 127. The removal of the shafts 137 will permit the reels 139 to be removed from the recesses. Each one of the shafts 137 is provided with a squared end 143a that may be engaged by a suitable key, or the like, for effecting its rotation.

This reel assembly is employed for supplying the strip of rupturable material 140 to the illustrated position between the cooperating end portions of the plunger 121 and the plug 142 so that longitudinally spaced portions may be positioned between the adjacent ends of the aligned passageways 136 and 143. To accomplish this desired result, one of the reels 139 has wound thereon a coil of the rupturable strip 140 when it is inserted in its recess 127 and secured therein by its supporting shaft 137. The other reel 139 will function as a take-up for the strip as longitudinally spaced portions of the latter are subjected to the shearing action which results from the venting of the control chamber section 132.

The extremities of the rupturable strip are suitably anchored to the hubs of the reels in the manner best illustrated in Figs. 10 and 11. After the rupturable strip 140 has been transferred from the supply reel to the take-up reel, the latter reel may be removed from its recess 127 and another reel, with a supply of strip material coiled thereon, may be substituted. The original supply reel 139 then may be used as the take-up reel for the new strip of material.

The cartridge, assembled as described above, has formed within the discharge and venting sections 31 and 105, respectively, and between the main valve 109 and plunger 121 a control chamber 131 which is divided into an outer or pilot section 132 and an inner main section 133 by the pilot valve 115. The main section 133 of the

control chamber is in communication with the charge release chamber 13 through an aperture 134 in the main valve 109. The main and pilot sections 133 and 132, respectively, are in communication with each other through an aperture 135 formed in the pilot valve 115. A passageway 136 extends axially through the body portion of the plunger 121 and its projection 126. The diameters of the apertures 134 and 135 in the main valve 109 and pilot valve 115, respectively, are smaller than that of the passageway 136 in the plunger 38 for reasons that later will be described. Ratios of aperture diameters to the passageway diameter ranging from one-half to one-third have been found to be satisfactory.

A plug 142 is threaded into the outer portion of the pocket 125 into contact with the strip 140 to move the strip and its engaging plunger projection 126 a slight distance against the pressure of the spring 119. The plug 142 is formed with an axially located passageway 143 of equal size to and in alignment with the passageway 136 in the plunger 121. The outer end of the passageway 143 intersects a transverse passageway 144 through the outer end of the plug 142.

The operation of the cartridge illustrated in Figs. 9 to 11, inclusive, will be described as follows:

The cartridge, in a condition for being charged with compressed air or other gas, is placed in a previously prepared drill hole formed in the working face of the material to be broken down, such as coal in a mine. At this time, the charge release chamber 13 of the cartridge body 12 is sealed from the discharge ports 33 by the engagement of the main valve 109 with its valve seat 29 and by the packing ring 113, and the main section 133 of the control chamber 131 is sealed from the venting ports 107 by the engagement of the pilot valve 115 with its valve seat 108 and by the packing ring 118. The aligned passageways 136 and 143 in the plunger 121 and plug 142, respectively, are sealed from each other by the shear strip 140. The charge release chamber 13 is, however, in communication with the main and pilot sections 133 and 132, respectively, of the control chamber 131 through the apertures 134 and 135 in the main valve 109 and pilot valve 115, respectively.

The compressed air in the charge release chamber 13 is rapidly built up to the desired work performing pressure. During this charging of the chamber 13, compressed gas is permitted to flow into the main and pilot sections 133 and 132, respectively, through the apertures 134 and 135. The pressure in these sections of the control chamber 131, therefore, will be substantially equal to the pressure in the charge release chamber 13 at all times. The main valve 109 will be maintained in its seated or closed position by the force of the spring 114 and the differential force acting upon the valve. In other words, the effective surface area of the valve 109 exposed to the pressure in the charge release chamber 13, the forces acting upon the valve 109 are unbalanced in a direction to maintain the valve in its closed position. The pilot valve 115, also, will be maintained in its seated or closed position by the force of the spring 119 and the differential force acting upon opposite sides of the valve. This differential force on valve 115 is due to the greater effective surface area exposed to the pressure in the pilot section 132 of the control chamber 131 than the effective surface area of the pilot valve exposed to the pressure in the main section 133 of the control chamber.

When the charge release chamber 13 and both sections of the control chamber 131 have received a sufficient volume of gas to raise the pressures therein to the desired work performing value, the pressure of the gas in the pilot section 132 of the control chamber will cause the exposed portion of the strip 140 to be sheared and blown out through the passageways 143 and 144. Inasmuch

as the strip 140 is wrapped onto and off of the reels 139, the strip is formed of ductile or flexible material, the shear strength of which is necessarily limited. This limited shear strength is, however, compensated for by a reduction in the diameters of the passageways 136 and 143 so that the cartridge will be discharged when the pressure therein reaches the proper value.

When the strip 140 is sheared, the pilot section 132 of the control chamber 131 is vented through the passageways 143 and 144 in the plug 142 to quickly reduce the pressure in the pilot section. This reduction in the pressure permits the pressure of the compressed gas in the main control section 133 to open the pilot valve 115 to release the gas from the main section through the venting ports 107. This venting of the main section 133 will quickly reduce the pressure therein to permit the pressure of the gas in the charge release chamber 13 to open the main valve 109 for release of the gaseous charge through the discharge ports 33. After the gas in the charge release chamber 13 has been discharged, the pressure in the charge release chamber and both sections of the control chamber 131 will be at atmospheric pressure and the springs 114 and 119 will cause the main valve 109 and the pilot valve 115, respectively, to be returned to their seated or closed positions.

The strip 140, which is initially clamped in position across the aligned passageways 136 and 143 only by the pressure of the spring 119, is clamped in position with a considerably greater force during charging of the cartridge by the pressure of the gas in the pilot section 132 of the control chamber 131 acting on the plunger 121. When the cartridge is discharged, however, the pressure in the pilot section 132 is reduced to atmospheric pressure and the strip 140 is again clamped only by the pressure of the spring 119 on the plunger 121. The plug 142, therefore, may be loosened or moved outwardly by hand to permit the plunger 121 to move outwardly until its body portion bears against the cap 124. Further movement of the plug 142 then will release the strip 140. The strip 140 thereafter may be moved longitudinally through the slots 128 by rotation of the take-up reel 139 to position an unsheared portion of the strip across the aligned passageways 136 and 143. This repositioning of the strip 140 and tightening of the plug 142 to move the strip 45 and plunger 121 a sufficient distance for the strip to be clamped by the action of the spring 119 reconditions the cartridge for a subsequent operation.

As was previously pointed out, the passageway 136 is of larger cross-sectional area than the aperture 135 in the pilot valve 115 so that venting of the gas from the pilot section 132 will greatly exceed the rate of flow of gas through the aperture 135. Similarly, the flow of gas through the venting ports 107 when the pilot valve 115 is opened will cause the main section 133 of the control chamber to be vented at a rate greatly exceeding the flow of gas through the aperture 134 in the main valve 109.

It will be appreciated that the venting caps 49 of the different cartridges illustrated in Figs. 1 to 8, inclusive, are each interchangeable with the venting cap 124 of the cartridge illustrated in Figs. 9 to 11, inclusive. In other words, the venting cap 124, with its supply and take-up reels for the strip of rupturable material, may be used with any one or all of the different cartridges illustrated in Figs. 1 to 8, inclusive, while the venting caps 49 of these last mentioned cartridges may be employed with the cartridge of Figs. 9 to 11, inclusive.

It is to be understood that the forms of this invention herewith shown and described are to be taken as preferred examples of the same and that various changes in the shape, size, and arrangement of parts may be resorted to without departing from the spirit of the invention or the scope of the subjoined claims.

Having thus described the invention, we claim:

1. In combination, a cartridge having a chamber from

which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means responsive solely to an increase in the gas pressure in the control chamber to a predetermined value for automatically releasing the gas from said control chamber to cause the gas in the release chamber to open the valve, said venting means comprising an elongated strip of rupturable material, and means for clamping said strip to expose a selectable portion of it to the pressure of the gas in said control chamber to cause the exposed portion to be sheared by the control chamber pressure when said predetermined value is reached.

2. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chamber reaches a predetermined value, said venting means comprising an elongated strip of rupturable material, and means for clamping said strip to expose a limited portion of the latter to the pressure of the gas in said control chamber to cause the exposed portion to be sheared by the control chamber pressure when said predetermined value is reached, said clamping means being adjustable to release and reclamp the strip so that the latter may be moved to successively expose other unsheared limited portions to the control chamber pressure to condition the venting means for repeated operations of the cartridge.

3. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising an elongated strip of rupturable material, and means for clamping said strip to expose a limited portion of the latter to the pressure of the gas in said control chamber to cause the exposed portion to be sheared by the control chamber pressure when said predetermined value is reached, said clamping means comprising one part that is subject to the control chamber pressure so as to vary the clamping force applied to the strip substantially in proportion to said pressure and a second part manually adjustable to release and reclamp the strip, when said one part is subjected to a low control chamber

pressure, so said strip may be moved to successively expose other unsheared limited portions to the control chamber pressure to condition the venting means for repeated operations of the cartridge.

5. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising an elongated strip of rupturable material, means movable into clamping engagement with said strip for maintaining the strip in a position to expose a limited portion thereof to the pressure of the gas in said control chamber 20 and to cause the exposed portion to be sheared by the control chamber pressure when said predetermined value is reached, resilient means urging said clamping means in a direction for loosely clamping said strip in said position, means responsive to the pressure in said control chamber for increasing the clamping forces of the movable means as the pressure in the chamber is increased, and means for disengaging said strip from said movable means when the strip is in its loosely clamped condition for movement of the strip to expose a different longitudinally spaced portion of the latter during each succeeding operation of the cartridge.
5. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising an elongated strip of rupturable material, plug means threadedly mounted on said cartridge for engaging a portion of one face of said strip outwardly of said control chamber, plunger means mounted for movement in said control chamber for engaging the opposite face of said strip to clamp the strip against the plug with a limited portion of the strip exposed to the pressure in said control chamber so as to be sheared by said pressure when said predetermined value is reached, and resilient means urging said plunger means into clamping engagement with the strip, said plunger means being subject to the pressure in said control chamber to vary the clamping force on said strip, said plug means being adjustable away from and toward said plunger means to release and reclamp the ruptured strip so the latter may be moved to successively expose unsheared limited portions to the control chamber pressure to condition the venting means for repeated operations of the cartridge.
6. In combination, a cartridge having a chamber from which a material breaking charge of compressed gas is to be released, lateral gas charge release ports, and a control chamber arranged successively longitudinally of

said cartridge, a valve for controlling the release of the gas charge from said gas release chamber to the release ports and being exposed to the pressure of the gas in said control and release chambers with a greater effective surface area exposed to said control chamber than said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising a plug threadedly connected to said cartridge, a plunger mounted in said control chamber for limited movement relative to said plug, an elongated strip of rupturable material insertable between said plug and said plunger with a limited portion of the strip exposed to and to be sheared by the pressure in said control chamber to effect said automatic release of the gas from the control chamber when said predetermined value is reached, resilient means urging said plunger toward said plug to initially clamp the strip therebetween, said plunger having means responsive to the pressure in said control chamber for increasing the clamping action of said plunger as the pressure in the control chamber is increased to its predetermined value, said plug being adjustable away from and toward said plunger to release and reclamp said strip so that the latter may be moved to successively expose unsheared limited portions to the control chamber pressure to condition the venting means for repeated operations of the cartridge.

7. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising a plug connected to said cartridge and having a passageway therethrough, a plunger mounted in said control chamber for limited movement relative to said plug and having a passageway therethrough in alignment with the passageway through said plug, an elongated strip of rupturable material insertable between the adjacent ends of the aligned passageways in said plug and plunger, the portion of said strip between said passageways being sheared by the pressure in said control chamber to effect said automatic release of the gas from the control chamber when said predetermined value is reached, means for moving said plunger toward said plug to clamp the strip therebetween, and means for adjusting said plug away from and toward said plunger to release and reclamp the strip so the latter may be moved to successively position unsheared portions between the adjacent ends of said passageways to condition the venting means for repeated operations of the cartridge.

8. In combination, a cartridge having a chamber from which a material breaking charge of compressed gas is to be released, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release

and control chambers, and venting means for automatically releasing the gas from said control chamber to cause the gas in the release chamber to open the valve when the pressure in said chambers reaches a predetermined value, 5 said venting means comprising a plug connected to said cartridge and having a passageway therethrough, a plunger mounted in said control chamber for limited movement relative to said plug and having a passageway therethrough in alignment with the passageway through the plug, an 10 elongated strip of rupturable material insertable between the adjacent ends of the aligned passageways in said plug and plunger, the portion of said strip between said passageways being sheared by the pressure in said control chamber to effect automatic release of the gas from the control chamber when said predetermined value is reached, 15 resilient means urging the aforesaid valve toward its closed position and urging said plunger toward said plug to clamp the strip therebetween, said plunger having a piston portion acted on by the pressure in said control chamber 20 for increasing the clamping force exerted by said plunger as the pressure in the control chamber increases, and means for adjusting said plug away from and toward said plunger to release and reclamp the strip so the latter may be moved to successively position unsheared portions between the adjacent ends of said passageways to condition the venting means for repeated operations of the cartridge.

9. In combination, a cartridge having a chamber from which a material breaking charge of compressed gas is to be released, lateral gas charge release ports, and a control 30 chamber arranged successively longitudinally of said cartridge, a valve for controlling the release of the gas charge from said gas release chamber to the release ports and being exposed to the pressure of the gas in said control and release chambers with a greater effective surface area 35 exposed to said control chamber than said release chamber, means for equalizing the gas pressures in the release and control chambers, resilient means urging said valve into its closed position, and venting means for automatically releasing the gas from said control chamber to cause 40 the gas in the release chamber to open the valve when the pressure in said chambers reaches a predetermined value, said venting means comprising a plug threadedly mounted on said cartridge and having a passageway therethrough, a plunger mounted in said control chamber for limited 45 movement toward and away from said plug and having a passageway therethrough in alignment with the passageway through said plug, and an elongated strip of material positioned between said plug and plunger across the aligned passageways, the portion of said strip across said passageways being rupturable by the pressure in said control chamber to effect said automatic release of the gas from the control chamber when said predetermined value is 50 reached, said resilient means urging said plunger toward said plug to clamp the strip therebetween, and said plug being manually movable away from said plunger to release the ruptured strip for movement to place a different longitudinally spaced portion of the latter across said passageways during each succeeding operation of the cartridge.

10. In combination, a cartridge having a chamber from 60 which a material breaking charge of compressed gas is to be released, lateral gas charge release ports, and a control chamber arranged successively longitudinally of said cartridge, a valve for controlling the release of the gas charge from said gas release chamber to the release ports and 65 being exposed to the pressure of the gas in said control and release chambers with a greater effective surface area exposed to said control chamber than said release chamber, means for equalizing the gas pressures in the release and control chambers, resilient means urging said valve into its closed position, and venting means for automatically releasing the gas from said control chamber to cause 70 the gas in the release chamber to open the valve when the pressure in said chambers reaches a predetermined value, said venting means comprising a plug threadedly mounted on said cartridge and having an axially located

passageway therein, said plug also having radially directed passageways between said axially located passageway and its threaded surface, a plunger mounted in said control chamber for limited movement toward and away from said plug and having a passageway therethrough in alignment with the axially located passageway in said plug, and an elongated strip of material positioned between said plug and plunger across the aligned passageways, the portion of said strip across said passageways being rupturable by the pressure in said control chamber to effect said automatic release of the gas from the control chamber when said predetermined value is reached, flow of gas through the aligned passageways effecting a limited flow of gas through said radial passageways to remove any dust particles from between the threaded surfaces of said plug and cartridge, said resilient means urging said plunger toward said plug to clamp the strip therebetween, and said plug being movable away from said plunger to release the ruptured strip for movement to expose a different longitudinally spaced portion of the latter during each succeeding operation of the cartridge.

11. In combination, a cartridge body having arranged successively longitudinally thereof in the order named a chamber in which a material breaking charge of compressed gas is to be developed and from which the charge is to be released, lateral gas charge release ports, and a control chamber, valve means positioned in the cartridge body between the release chamber and the control chamber and having a greater effective surface area exposed to said control chamber pressure than to said release chamber pressure, resilient means normally urging the valve means toward a position to seal the release ports from the release chamber, means for passing gas from said release chamber to said control chamber to equalize at a retarded rate the gas pressure in the control chamber with the gas pressure in the release chamber as the charge is developed in the latter chamber, and means responsive solely to an increase in the gas pressure in the control chamber to a predetermined value for lowering the gas pressure in said control chamber at a greater rate than said retarded rate to reduce the control chamber pressure to a value substantially below that of the gas in the release chamber and to cause the gas pressure in the release chamber to move the valve into a position to unseal the release ports.

12. In combination, a cartridge body having arranged successively longitudinally thereof in the order named a chamber in which a material breaking charge of compressed gas is to be developed and from which the charge is to be released, lateral gas charge release ports, and a control chamber, valve means positioned in the cartridge body between the release chamber and the control chamber and having a greater effective surface area exposed to said control chamber pressure than to said release chamber pressure, resilient means normally urging the valve means toward a position to seal the release ports from the release chamber, means for equalizing at a retarded rate the gas pressure in the control chamber with the gas pressure in the release chamber as the charge is developed in the latter chamber, and means responsive solely to an increase in the gas pressure in the control chamber to a predetermined value for quickly lowering the gas pressure in said control chamber substantially below the gas pressure in the release chamber to cause the gas pressure in the release chamber to move the valve into a position to unseal the release ports, said pressure lowering means comprising means for providing a venting passageway from the control chamber to the exterior of the cartridge body, and a rupturable member closing said passageway and sheared by the gas pressure in the control chamber when the latter reaches said predetermined value.

13. In combination, a cartridge body having arranged successively longitudinally thereof in the order named a chamber in which a material breaking charge of com-

pressed gas is to be developed and from which the charge is to be released, lateral gas charge release ports, and a control chamber, valve means positioned in the cartridge body between the release chamber and the control chamber and having a greater effective surface area exposed to said control chamber pressure than to said release chamber pressure, resilient means normally urging the valve means toward a position to seal the release ports from the release chamber, means for equalizing at a retarded rate the gas pressure in the control chamber with the gas pressure in the release chamber as the charge is developed in the latter chamber, and means for quickly lowering the gas pressure in said control chamber substantially below the gas pressure in the release chamber when the pressure in the control chamber reaches a predetermined value to cause the gas pressure in the release chamber to move the valve into a position to unseal the release ports, said pressure lowering means comprising relatively adjustable clamping members providing a passageway from the control chamber to the exterior of the cartridge body, and a strip of rupturable material held in position by the clamping members so as to have a limited portion of its length closing said passageway to be sheared by the gas pressure in the control chamber when the latter reaches said predetermined value, said clamping members being adjusted relative to each other to release and reclamp the strip so that the latter may be moved to successively position other unsheared portions of its length to close said passageway to condition the cartridge for repeated operations.

14. In combination, a cartridge body having arranged successively longitudinally thereof in the order named a chamber in which a material breaking charge of compressed gas is to be developed and from which the charge is to be released, lateral gas charge release ports, and a control chamber, valve means positioned in the cartridge body between the release chamber and the control chamber and having a greater effective surface area exposed to said control chamber pressure than to said release chamber pressure, resilient means normally urging the valve means toward a position to seal the release ports from the release chamber, means for equalizing at a retarded rate the gas pressure in the control chamber with the gas pressure in the release chamber as the charge is developed in the latter chamber, and means for quickly lowering the gas pressure in said control chamber substantially below the gas pressure in the release chamber when the pressure in the control chamber reaches a predetermined value to cause the gas pressure in the release chamber to move the valve into a position to unseal the release ports, said pressure lowering means comprising a first clamping member movably positioned in the control chamber to be subjected to the gas pressure therein, a second clamping member threadedly connected to the cartridge body at the outer end of the control chamber so as to cooperate with the first clamping member, said clamping members providing a passageway from the control chamber to the exterior of the cartridge body, and a strip of rupturable material held in position by the clamping members so as to have a limited portion of its length closing said passageway to be sheared by the gas pressure in the control chamber when the latter reaches said predetermined value, said second clamping member being threadedly adjusted relative to the first clamping member to release and reclamp the strip so that the latter may be moved to successively position other unsheared portions of its length to close said passageway to condition the cartridge for repeated operations.

15. A cartridge as defined in claim 11 further characterized by the control chamber having a pilot valve movably mounted therein for dividing the chamber into inner and outer sections, and having a greater effective surface area exposed to the outer chamber section pressure than to the inner chamber section pressure, said inner section having a lateral gas venting port, and re-

silient means in the control chamber normally holding the pilot valve in the position to seal the vent port from the inner control chamber section.

16. A cartridge as defined in claim 12 further characterized by a pilot valve movably mounted in the control chamber to divide the chamber into inner and outer sections and having a greater effective surface area exposed to the outer chamber section pressure than to the inner chamber section pressure, said inner section having a lateral gas venting port, and resilient means in the control chamber normally holding the pilot valve in the position to seal the vent port from the control chamber section, said pilot valve being moved into a position to unseal the vent port by the gas pressure in the inner control chamber after said rupturable member is sheared.

17. A cartridge as defined in claim 13 further characterized by means carried by said cartridge for storing the unsheared portion of the rupturable strip prior to being moved into position between the clamping members and for receiving the sheared portion of said strip after being moved past said position.

18. In combination, a cartridge body having arranged successively longitudinally thereof in the order named a chamber in which a material breaking charge of compressed gas is to be developed and from which the charge is to be released, lateral gas charge release ports, and a control chamber receiving compressed gas from the release chamber at a rate which will maintain the pressure in the control and release chambers substantially equal during development of said charge in the release chamber, valve means positioned in the cartridge body between the release chamber and the control chamber for sealing the release ports, and means responsive solely to an increase in the gas pressure in the control chamber to a predetermined value for lowering the gas pressure in said control chamber at a greater rate than the aforesaid rate at which the control chamber receives gas from the release chamber to reduce the control chamber pressure to a value substantially below that of the gas in the release chamber and to cause the gas pressure in the release chamber to move the valve into a position to unseal the release ports.

19. Discharge mechanism for a compressed gas material breaking cartridge, comprising a tubular discharge section having one end portion to be detachably connected to a cartridge body and lateral discharge ports adjacent said end portion, means forming a valve seat in said end portion, valve means movably positioned in the discharge section, resilient means normally urging the valve means toward the valve seat to seal the release ports, a cap connected to the remaining end portion of the discharge section and forming a control chamber in the section between the valve means and said cap, and means carried by the cap and responsive solely to an increase in the gas pressure in the control chamber to a predetermined value for venting the control chamber.

20. Discharge mechanism for a compressed gas material breaking cartridge, comprising a tubular discharge section having one end portion to be detachably connected to a cartridge body and lateral discharge ports adjacent said end portion, means forming a valve seat in said end portion, valve means movably positioned in the discharge section, resilient means normally urging the valve means toward the valve seat to seal the release ports, a cap connected to the remaining end portion of the discharge section and forming a control chamber in the section between the valve means and said cap, and means carried by the cap and responsive solely to an increase in the gas pressure in the control chamber to a predetermined value for venting the control chamber, said control chamber venting means comprising means for providing a venting passageway for the control chamber, and a rupturable member closing said passageway and sheared by the gas pressure in the control chamber when the latter reaches said predetermined value.

21. Discharge mechanism for a compressed gas ma-

terial breaking cartridge, comprising a tubular discharge section having one end portion to be detachably connected to a cartridge body and lateral discharge ports adjacent said end portion, means forming a valve seat in said end portion, valve means movably positioned in the discharge section, resilient means normally urging the valve means toward the valve seat to seal the release ports, a cap connected to the remaining end portion of the discharge section and forming a control chamber in the section between the valve means and said cap, and means carried by the cap for venting the control chamber when the gas pressure in said chamber reaches a predetermined value, said control chamber venting means comprising relatively adjustable clamping members providing a venting passageway for the control chamber, and a strip of rupturable material held in position by the clamping members so as to have a limited portion of its length closing said passageway to be sheared by the gas pressure in the control chamber when the latter reaches said predetermined value, said clamping members being adjusted relative to each other to release and reclamp the strip so that the latter may be moved to successively position other unsheared portions of its length to close said passageway to condition the discharge mechanism for repeated operations.

22. Discharge mechanism for a compressed gas material breaking cartridge, comprising a tubular discharge section having one end portion to be detachably connected to a cartridge body, and lateral discharge ports adjacent said end portion, means forming a valve seat in said end portion, valve means movably positioned in the discharge section, resilient means normally urging the valve means toward the valve seat to seal the release ports, a cap connected to the remaining end portion of the discharge section and forming a control chamber in the section between the valve means and said cap, and means carried by the cap for venting the control chamber when the gas pressure in said chamber reaches a predetermined value, said control chamber venting means comprising a first clamping member movably positioned in the control chamber to be subjected to the gas pressure therein, a second clamping member threadedly connected to the cap to cooperate with the first clamping member, said clamping members providing a venting passageway for the control chamber, and a strip of rupturable material held in position by the clamping members so as to have a limited portion of its length closing said passageway to be sheared by the gas pressure in the control chamber when the latter reaches said predetermined value, said second clamping member being threadedly adjusted relative to the first clamping member to release and reclamp the strip so that the latter may be moved to successively position other unsheared portions of its length to close said passageway to condition the discharge mechanism for repeated operations.

23. In combination, a cartridge having a chamber from which a material breaking charge of compressed gas is to be released on the rupture of a rupturable member, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising means for clamping said rupturable member in said cartridge to expose a limited portion thereof to the pressure of the gas in said control chamber to cause

said portion to be ruptured by the control chamber pressure when said predetermined value is reached, said clamping means comprising one part that is subject to the control chamber pressure so as to vary the clamping force applied to said rupturable member substantially in proportion to said pressure and a second part manually adjustable in said cartridge to clamp said rupturable member between said parts.

24. Discharge mechanism for a compressed gas material breaking cartridge the release of which gas is effected by the rupture of a rupturable member, said cartridge comprising a tubular discharge section having one end portion to be detachably connected to a cartridge body and lateral discharge ports adjacent said end portion, means forming a valve seat in said end portion, valve means movably positioned in the discharge section, resilient means normally urging the valve means toward the valve seat to seal the release ports, a cap connected to the remaining end portion of the discharge section and forming a control chamber in the section between the valve means and said cap, and means carried by the cap for venting the control chamber when the gas pressure in said chamber reaches a predetermined value, said control chamber venting means comprising relatively adjustable clamping members providing a venting passageway for the control chamber and adapted to be positioned on opposite sides of said rupturable member and to have sealing engagement therewith.

25. In combination, a cartridge having a chamber from which a material breaking charge of compressed gas is to be released on the rupture of a rupturable member, lateral gas charge release ports, and a control chamber arranged successively longitudinally of said cartridge, a valve for controlling the release of the gas charge from said gas release chamber to the release ports and being exposed to the pressure of the gas in said control and release chambers with a greater effective surface area exposed to said control chamber than to said release chamber, means for equalizing the gas pressures in the release and control chambers, resilient means urging said valve into its closed position, and venting means for automatically releasing the gas from said control chamber to cause the gas in the release chamber to open the valve when the pressure in said chambers reaches a predetermined value, said venting means comprising first and second clamping members providing a passageway therethrough to the exterior of the cartridge body and being disposed on opposite sides of said rupturable member so that a restricted portion thereof closes said passageway and one side thereof is in direct contact with said gas, said second clamping member being secured to said cartridge body and reacting against the other side of said rupturable member to cooperate with said first clamping member and provide a preliminary seal with said rupturable member, said first clamping member being movably positioned in said cartridge body and subjected to the gas therein to increase the clamping force applied to said rupturable member in proportion to said pressure and provide the final seal with said rupturable member.

26. In a compressed gas chamber the discharge of which is controlled by a shear element, the improvement which comprises means forming a passageway to be closed by said shear element, said passageway forming means comprising an inner member having one portion of said passageway therewithin and an outer member in end-to-end alignment with said inner member axially of the chamber and having another portion of said passageway therewithin as an endwise continuation of said one portion, said outer member being adjustably carried by the chamber and said members being movable endwise relatively toward each other to clamp and seal said shear element therebetween in a preliminary closing and sealing relationship with the passageway, said inner

member being separate and distinct from said chamber and exposed to and movable outwardly by the pressure of the gas in the chamber to vary the sealing forces applied to the shear element by the inner and outer members substantially in proportion to said gas pressure to clamp and seal said shear element therebetween in a final clamping and sealing relationship so that the shear element may be easily removed and replaced after the chamber has been discharged, said inner member being movable toward said outer member no further than required to effect said clamping and sealing relationship, means within said chamber limiting the inward movement of said inner member to provide said preliminary seal, and the portion of said shear element closing said passageway being sheared from the remainder of the element to effect automatic release of gas through said passageway when the pressure of the gas is increased to a determined value.

27. In a compressed gas chamber the discharge of which is controlled by a shear element, the improvement which comprises means forming a passageway to be closed by said shear element, said passageway forming means comprising an inner member and an outer member in endwise axially spaced relation thereto, said outer member being adjustably carried by the chamber, the passageway within one member continuing axially endwise into the other member, said members being movable endwise relatively toward each other and having opposed metallic surfaces surrounding said passageway for clamping and sealing said shear element therebetween in a preliminary closing and sealing relationship with the passageway, said inner member being separate and distinct from said chamber and exposed to and movable outwardly by the pressure of the gas in the chamber to vary the sealing forces applied to the shear element by said clamping surfaces substantially in proportion to said gas pressure to clamp and seal said shear element therebetween in a final clamping and sealing relationship so that the shear element may be easily removed and replaced after the chamber has been discharged, means within said chamber limiting the inward movement of said inner member to provide said preliminary seal, and the portion of said shear element surrounded by said opposed surfaces and closing said passageway being sheared from the remainder of the element to effect automatic release of gas through said passageway when the pressure of the gas is increased to a predetermined value.

28. In a compressed gas chamber the discharge of which is controlled by a shear element, the improvement which comprises means forming a passageway to be closed by said shear element, said passageway forming means comprising an inner member, and an outer member carried by the chamber in axial endwise alignment for movement relative to each other to clamp and seal said shear element therebetween in a preliminary closing and sealing relationship with the passageway, there being one portion of said passageway within said inner member on one side of said shear element and another portion of said passageway constituting an endwise continuation of said one portion on the other side of said shear element within said outer member, said inner member being disposed wholly on the side of said shear element to which the gas pressure is applied and being separate and distinct from said chamber and exposed to and movable outwardly by the pressure of the gas in said chamber and having a peripheral seal to prevent the flow of gas between adjacent surfaces of the chamber and the inner member into direct contact with the shear element, variations in the pressure of the gas in the chamber effecting substantially proportional variations in the sealing forces applied to the shear element by said inner and outer members to clamp and seal said shear element therebetween in a final clamping and sealing relationship so that the

shear element may be easily removed from between said members after the chamber has been discharged, means within said chamber limiting the inward movement of said inner member to provide said preliminary seal, and the portion of said shear element closing said passageway being sheared from the remainder of the element to effect automatic release of gas through the passageway when the pressure of the gas is increased to a predetermined value.

29. In a compressed gas chamber the discharge of which is controlled by a shear element, the improvement which comprises means forming a passageway to be closed by said shear element, said passageway forming means comprising an inner member and an outer member, said outer member being adjustably carried by said chamber, said inner member being separate and distinct from and mounted in said chamber and guided by the chamber for outward movement toward said outer member by an increase in the gas pressure in said chamber, means forming a seal between surface portions of said inner member and chamber, and said outer member being adjustable into and out of clamping relationship with said inner member to clamp the shear element therebetween in a preliminary closing and sealing relationship with the passageway and to release the shear element so that the latter may be removed and replaced to condition the chamber for repeated operations, variations in the gas pressure in said chamber effecting substantially proportional variations in the clamping forces applied to said shear element by the inner and outer members to clamp and seal said shear element therebetween in a final clamping and sealing relationship so that the shear element is rigidly clamped to seal the passageway when the gas pressure in the chamber is increased and is loosely clamped to permit the aforesaid adjustment of the outer member to release the shear element after the chamber has been discharged, there being at least one transverse opening in the wall of said chamber in register with the portions of said inner and outer members between which said shear element is clamped for receiving said shear element and facilitating the removal of the remnant thereof after shearing of said element and discharging of the compressed gas, and means within said chamber limiting the inward movement of said inner member to provide said preliminary seal, the portion of said shear element closing said passageway being sheared from the remainder of the element to effect automatic release of gas through the passageway when the pressure of the gas is increased to a predetermined value.

30. In a compressed gas chamber the discharge of which is controlled by a shear element, the improvement which comprises means forming a passageway to be closed by said shear element, said passageway forming means comprising an inner member and an outer member having aligned portions of said passageway formed therein, said outer member being threadedly mounted on said chamber, said inner member being separate and distinct from and slidably mounted in said chamber for limited movement relative to said outer member to clamp and seal said shear element therebetween in a preliminary closing and sealing relationship with said passageway, and resilient means urging said inner member toward said outer member for loosely clamping the shear element therebetween when said outer member is threaded into clamping relationship with said inner member to provide said preliminary seal, said inner member being subject to the gas pressure in said chamber to increase the clamping force on said shear element substantially in proportion to increases in said gas pressure and to tightly seal said shear element between said inner and outer members in a final clamping and sealing relationship, and said outer member being adjustable away from and toward said inner member to permit the shear element to be removed and replaced when the portion of the element closing said passageway has been sheared from the remainder of the

element by an increase in the gas pressure in the chamber to a predetermined value to effect automatic release of gas through said passageway.

31. In a compressed gas chamber the discharge of which is controlled by a replaceable rupturable element, a body having a chamber for receiving a charge of highly compressed gas; means for clamping said rupturable element in sealing position in said body against the pressure exerted by said gas comprising first and second clamping members providing a passageway extending therethrough to the exterior of the body, each of said members being wholly disposed on opposite sides respectively of said rupturable element so that the central portion of said element closes said passageway and one side of said element is in direct contact with said gas, said second clamping member reacting against the other side of said rupturable element to cooperate with said first clamping member and provide a preliminary seal with said rupturable element, said first clamping member being separate, and distinct from and movable relative to said body and subject to outward movement by the gas therein to increase the clamping force applied to said rupturable element in proportion to said pressure and provide the final seal with said rupturable element; and means in said body limiting the inward movement of said first clamping member to provide said preliminary seal.

32. In a compressed gas chamber the discharge of which is controlled by a replaceable rupturable element, a body having a chamber for receiving a charge of highly compressed gas; means for clamping said rupturable element in sealing position in said body against the pressure exerted by said gas comprising first and second clamping members providing a passageway extending therethrough to the exterior of the body, said first and second members being wholly disposed on opposite sides of said rupturable element so that the central portion of said element closes said passageway and one side of the central portion of said element is in direct contact with said gas, said second clamping member reacting against the other side of said rupturable element to cooperate with said first clamping member and provide a preliminary seal with said rupturable element, said first clamping member being separate and distinct from and movable relative to said body and subject to outward movement by the gas therein to increase the clamping force applied to said rupturable element in proportion to said pressure and provide the final seal with said rupturable element, and peripheral sealing means between the inner surface of said body and the outer surface of said first clamping member to prevent the escape of gas between said surfaces into direct contact with the rupturable element; and means in said body limiting the inward movement of said first clamping member to provide said preliminary seal.

33. In a compressed gas chamber the discharge of which is controlled by a replaceable rupturable element, a body having a chamber for receiving a charge of highly compressed gas; means for clamping said rupturable element in sealing position in said body against the pressure exerted by said gas comprising first and second clamping members providing a passageway therethrough to the exterior of the body, said clamping members having aligned portions of said passageway formed therein and being disposed on opposite sides of said rupturable element so that a restricted portion thereof closes said passageway and a substantial portion of one side thereof is in direct contact with said gas, said second clamping member being secured to said body and reacting against the other side of said rupturable element to cooperate with said first clamping member and provide a preliminary seal with said rupturable element, said first clamping member being disposed wholly on the side of said rupturable element to which the gas pressure is applied and being separate and distinct from and movable relative to said body and subject to outward movement by the gas therein to increase the clamping force applied to said rupturable element in

proportion to said pressure and provide the final seal with said rupturable element, means for effecting screw threaded adjustment between said second clamping member and said body and being required to be screwed up only hand tight to provide the preliminary seal; there being at least one transverses opening in the wall of said body in register with the portions of said clamping members between which said rupturable element is clamped for receiving said element and facilitating the removal of the remnant thereof after rupture of said element and discharge of the compressed gas, and means in said body limiting the inward movement of said first clamping member to provide said preliminary seal.

34. In a compressed gas chamber the discharge of which is controlled by a replaceable rupturable element, a body having a chamber for receiving a charge of highly compressed gas; means for clamping said rupturable element in sealing position in said body against the pressure exerted by said gas comprising first and second clamping members providing a passageway therethrough to the exterior of the body and being disposed on opposite sides of said rupturable element so that a restricted portion thereof closes said passageway and one side thereof is in direct contact with said gas, said second clamping member being secured to said body and reacting against the other side of said rupturable element to cooperate with said first clamping member and provide a preliminary seal with said rupturable element, said first clamping member being separate and distinct from and movable

relative to said body and subject to outward movement by the gas therein to increase the clamping force applied to said rupturable element in proportion to said pressure and provide the final seal with said rupturable element, said second clamping member having threaded engagement with said body and being required to be screwed up only hand tight to provide the preliminary seal, there being one or more ports placing the threads between said second clamping member and said body in communication with said passageway to cause a portion of the gas to discharge into said threads and prevent the accumulation of dust therein; and means in said body limiting the inward movement of said first clamping member to provide said preliminary seal.
